Fig. 1 Fig. 2

Fig. 3

FIGURE 1 is a front elevational view of the cabinet showing my new design;

FIGURE 2 is a side elevational view thereof;

FIGURE 3 is a front perspective view thereof on an enlarged scale;

FIGURE 4 is an enlarged fragmentary front perspective view of the upper right-hand corner portion thereof;

FIGURE 5 is a fragmentary vertical sectional view on an enlarged scale taken along line 5-5 of FIGURE 1; and

FIGURE 6 is a fragmentary horizontal sectional view on an enlarged scale taken along line 6-6 of FIGURE 1.

The dominant features of my design reside in the portion shown in full lines on the drawing and is characterized by the configured projecting door panel in combination with the recession in the edge of the door frame all as best illustrated in FIGURES 4, 5 and 6.

I claim:

The ornamental design for a cabinet, substantially as shown and described.
